UNITED STATES PATENT OFFICE.

EDGAR A. CUSTER, OF PHILADELPHIA, PENNSYLVANIA.

STRUCTURE-LIFTING DEVICE FOR CASTING-MOLDS.

No. 905,851.

Specification of Letters Patent.

Patented Dec. 8, 1908.

Application filed June 26, 1908. Serial No. 440,455.

To all whom it may concern:

Be it known that I, EDGAR A. CUSTER, a citizen of the United States, residing at the city of Philadelphia, in the county of Philadelphia and State of Pennsylvania, have invented certain new and useful Improvements in Structure-Lifting Devices for Casting-Molds, of which the following is a specification.

10 My invention has relation to structure lifting devices for casting molds adapted for use particularly in conjunction with two-part molds carried on a turntable for freeing the cast structure after pouring the molten 15 mass forming the structure so as to prevent possible chilling of the surface of such cast structure due to material difference in temperature between the molten metal poured into the mold and the interior of the mold 20 receiving such mass; and in such connection the device of my present invention is especially adapted for use, in the system of pipe making shown and described in Letters Patent No. 870,817, dated November 12th, 25 1907, granted to me; and No. 887,070, dated May 12th, 1908, and in conjunction therewith particularly with a revolving turntable provided in the latter patent with molds and a pouring ladle with operating 30 mechanism, which forms the subject-matter of pending applications for United States Letters Patent Serial No. 419,142, and Serial No. 421,054, filed by me, respectively, March 4th and 14th, 1908, to both of which 35 applications recourse is made.

The nature and scope of my present invention in the defined connection and relation of the same, will be more fully understood from the following description taken 40 with the accompanying drawings forming part hereof, in which

Figure 1 is a top or plan view, in broken section, of a turntable with a series of two-part molds mounted thereon, and in respectively three different positions of the copes with respect to the drags of the molds as illustrated, each mold with a cast structure therein being lifted away from the interior respective walls of the molds by devices of 50 my present invention and shown in application thereto; and Figs. 2, 3 and 4, are, respectively, end elevational views of three positions of the cope with respect to the drag of each mold as illustrated in Fig. 1, upon a 55 turntable and in Fig. 3, is shown in cross-section on the line z , z , of Fig. 1, the stationary

device for actuating or tripping a weighted pawl for each arm for embracing the cast structure as the cope parts from the drag of the mold, in opening, after the formation of 60 the cast structure.

Referring to the drawings 5, is an ordinary turntable provided with a series of horizontally disposed molds 6, of the type, for example; as illustrated and described in Letters 65 Patent granted to me under date of May 12th, 1908, and No. 887,070. Each mold 6, consisting of a cope a , hinged to a drag b , and each mold interiorly provided with respectively semicircular recesses c , and c' , as illustrated in Figs. 2 and 3, and with pour-holes or gates d , d' and d'' , as clearly illustrated in Fig. 1. To each upper corner of both sides is pivoted a goose-neck-like depending gravity or weighted arm 7, formed at the bottom into 70 runner e , having a front curved face e' , and a rear projection e'' , for engaging the curved head f , of a counter-weighted pawl 8. The pawl 8, is pivoted to the stationary drag a , of each mold near the lower corner thereof, as 75 clearly and fully illustrated, in Figs. 2, 3 and 4.

In the closed position of the cope a , against the drag b , in Fig. 3, with the casting therein, the structure embracing gravity arm 7, on each side, will have assumed the position, as 80 illustrated in this figure and with the curved head f , of the pawl 8, bearing against the front face e' , of the bottom of the embracing arm 7, freed from the pawl, and with the latter ready by the tripping device 10, projecting from the standards 11 and 12, as illustrated in Fig. 1, adjacent to the table 5, by contracting with the weight g , of the pawl to shift the same and head of the pawl 8, along over the flat bottom e , of the structure embracing arm 7, and so to lift the then formed structure 13, together with its internal composition core 14, away from the cope b , of the mold 6, and to thereby swing the same into a 100 space formed by the parting of the cope from the drag between the cope a , and drag b , aided by the counter-weighted pawl 8, due to the angular character thereof, by the head thereof engaging the projection e' , of the bottom of the arm 7, as clearly and fully illustrated 105 in Fig. 4. Before the mold is closed, that is the cope a , against the drag b , the composition core 14, will occupy the position in the recess of the drag b , and the embracing arms 7 and counter-weighted angular pawl 8, will 110 assume when the mold is in such position, that fully illustrated in Fig. 2, ready by the

device 10, riding along the weight of the pawl 8, to change to the position shown in Fig. 3, and then when the casting of the structure is completed to shift to the position, as illustrated in Fig. 4, from which suspended position, the cast structure can then be removed in any preferred manner, while the counter-weighted pawl 8, is locked to the projection e^2 , of the arm 7, by means of the weight of the 10 said pawl 8.

The instant the structure is cast from a molten mass, the head of the pawl 8, tends to shove the arms 7, to open the cope a , from the drag b , and in so doing, is overcome the 15 center of gravity between the two-parts of the mold b , and the arms 7, and pawls 8, and as the pawl tends to describe a curve the forward portion of the overbalanced arms 7, move forward and thereby the heads of the 20 pawls 8, slide along the bottom of the arms 7, until the projections e^2 , engage the tips of the heads of the pawls 8, to hold the same aided by the weighted ends thereof, in their respective assumed angular positions with respect to each other, as illustrated in Fig. 4.

The gripping of the cast structure quickly upon the parting of the cope a , from the drag b , of the mold 6, owing to the material differences in temperature between the metal of 30 the structure and internal surfaces of the mold prevents possible chilling of the surface of the cast structure, and hence permitting the cast structure almost the instant cast to be brought into a space created and in which 35 after chilling down of the metal quickly and cooling thereafter gradually, at the surrounding atmospheric temperature, the structure remains supported, for a short period and until the said cast structure is placed among 40 a pile of similar structures so cast to anneal by their own heat, under surrounding atmospheric conditions.

Having thus described the nature and objects of my invention, what I claim as new 45 and desire to secure by Letters Patent is:

1. Means of the character described, com-

prising a mold, composed of a movable cope and a fixed drag, an embracing structure device pivoted to the cope on each side, near the top thereof, and a counter-weighted 50 pawl-device pivoted to the drag on each side near the bottom thereof, said counter-weighted pawl-device adapted to ride said embracing structure device and to lock the same, in a certain position thereof. 55

2. Means of the character described, comprising a mold, composed of a movable cope and a fixed drag, an embracing structure device pivoted to the cope on each side near the top thereof and a counter-weighted pawl-device pivoted to the drag on each side near the bottom thereof, said counter-weighted 60 pawl-device adapted to ride said embracing structure device and to lock the same, in a certain position and means to release the 65 locked devices.

3. Means of the character described, comprising a traveler mold, consisting of a cope and a drag, an embracing structure device connected with the cope on each side near 70 the top thereof, a weighted pawl-device connected with the drag near the bottom thereof and adapted to lock said embracing device in a certain position and means for releasing said pawl-device from its locked position. 75

4. Means of the character described, comprising a traveler mold, consisting of a movable cope and a fixed drag, a weighted embracing structure device having a projection, said device connected with the cope and a 80 weighted pawl-device connected with the drag and adapted to lock with said embracing device and means to permit of the release of one from the other, after freeing the structure from said cope and drag. 85

In witness whereof, I have hereunto set my signature in the presence of two subscribing witnesses.

EDGAR A. CUSTER.
